Primary Examiner — Susan Bennett Hattan*Assistant Examiner* — Barbara B Lohr(74) *Attorney, Agent, or Firm* — Bunchanan Ingersoll & Rooney PC(57) **CLAIM**

The ornamental design for a Roman shade having a liner, as shown and described.

DESCRIPTION

FIG. 1 is a front elevated isometric view of the Roman shade having a liner in an extended position;

FIG. 2 is a front view of the Roman shade having a liner;

FIG. 3 is a rear view of the Roman shade having a liner;

FIG. 4 is a right side view of the Roman shade having a liner;

FIG. 5 is a left side view of the Roman shade having a liner;

FIG. 6 is a top view of the Roman shade having a liner;

FIG. 7 is a bottom view of the Roman shade having a liner;

FIG. 8 is a cross sectional view of the Roman shade with a line taken along line VIII-VIII in FIG. 3; and,

FIG. 9 is a front elevated isometric view of the Roman shade having a liner in a retracted position.

Stitching is shown in chain line in FIG. 3 and forms no part of the claimed design.
The Roman shade having a liner is shown broken away in FIGS. 1, 2, 3, 4, and 5 to indicate indeterminate length.**1 Claim, 6 Drawing Sheets****US D651,438 S**
